UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

HOPPER CAR AND THE LIKE.

Application filed May 14, 1924. Serial No. 713,132.

To all whom it may concern:

Be it known that I, ARGYLE CAMPBELL, a citizen of the United States, residing at Chicago, in the county of Cook and State 5 of Illinois, have invented a certain new and useful Improvement in Hopper Cars and the like, of which the following is a full, clear, concise, and exact description, reference being had to the accompanying drawings, 10 forming a part of this specification.

This invention relates to improvements in hopper cars and the like.

An object of the invention is to provide a load discharging car suitable for discharging its entire load either between the rails, 15 or to the sides thereof or partially to one side and partially to the other side of the rails.

A further object of the invention is to provide in a car of the character indicated 20 additional means on the exterior of the car whereby the adaptability and usefulness of the car in discharging its load, is extended, and which will render such a car particularly useful for ballast service.

25 A further object of my invention is to provide a car having center and side dump doors so arranged that the dumping doors may be conveniently and safely operated from transversely extending shafts operating other shafts extending longitudinally 30 of the car and suitably connected with the doors in the novel manner hereinafter described.

The invention furthermore consists in the 35 improvements in the parts and devices and in the novel combinations of the parts and devices, herein shown, described or claimed.

In the drawings, forming a part of this 40 specification, Figure 1 is a side, elevational view of the central portion or that portion contained between the sloping floors of a hopper car showing my improvements in connection therewith. Figure 2 is an enlarged, transverse, vertical, sectional view 45 taken through the car, corresponding substantially to line 2--2 of Figure 1. Figure 3 is a horizontal, sectional view corresponding substantially to line 3--3 of Figure 1. Figure 4 is a transverse, vertical, sectional view 50 corresponding substantially to line 4--4 of Figure 1. Figure 5 is a transverse, sectional view through the cross-beam corresponding substantially to line 5--5 of Figure 4.

55 In said drawings A--A denote the sides

of the car, B--B the sloping end walls, and C the centersill construction which, in the form shown comprises a plurality of channels 10--10 and a cover plate 11 forming a girder-like structure. Intermediate the 60 sloping end walls the car is provided with a hopper section which, as shown, consists of four hoppers D, longitudinally arranged in pairs on each side of the center sill, the hoppers being separated from each other by 65

the transversely extending crossbeam E consisting of two sets of inclined shedding plates 12--12 disposed on either side of the centersill C and united together by means of a flanged, vertical member 13 extending 70 across the plane of the centersill and united directly thereto by means of brackets 14. Effective connection is made between the crossbeam and side wall A of the car by means of gusset members 15 which are secured directly to the walls, and by means of angle members 16 which are secured to the wall and the respective gusset members. A direct connection between each gusset 75 member 15 and the member 13 is effected by 80 means of a series of rivets 17 and also by means of the inclined shedding plates 12--12 which are secured directly to the gussets 15 at 85 18 and to the vertical member at 19, thereby giving a continuous beam of great 90 strength extending between the side walls of the car and one of sufficient strength to transmit the load from the center sill to the deep side girders A of the car. Said inclined sheets 12 are extended downwardly 95 in a transverse, vertical plane as indicated at 20, each forming one end wall of one of the hoppers D, the opposite wall of each hopper being formed by the corresponding portion of one of the sloping end floors B and the corresponding transversely extending, vertical plate 21 depending therefrom.

As most clearly shown in Figure 3, each hopper is provided with an outer downwardly and inwardly inclined bottom sheet 22 and an inner, downwardly and outwardly inclined bottom sheet 23, said bottom sheets 22 and 23 forming substantially half of the bottom of the hoppers. The remaining portions of the hopper bottoms are formed by side 100 dumping hinged doors F and center dumping hinge doors G, the former being hinged along their upper edges substantially at the lower edges of the hopper sheets 22, as indicated at 24, the lower edge of the sheet 110

being suitably rigidified by a longitudinal extending member 25 and suitably braced to the side wall of the car by diaphragms 26. The center dumping doors G are hinged 5 along their upper edges substantially along the bottom edges of the hopper sheets 23, as indicated at 27. The lower edge of the sheet is suitably braced to the centersill by a longitudinally extending member 28. Each 10 pair of doors F—G for each hopper when in closed position are preferably adapted to have their lower edges meet as indicated at 29 and also preferably centrally over the rail 30, as indicated in Figure 2. For purposes of strength, all of the doors F and G are suitably braced by angles 31 and Z-bars 32 or other suitable commercial structural shapes.

Extending lengthwise of the car, and on 20 the outer sides of the hoppers, are operating shafts 33, the latter being adapted to operate the outer set of dumping doors F by means of flexible connections 34, the latter each having one end connected to a winding 25 sheave 35 secured to the corresponding shaft 33 and having the other end secured to the door F. The flexible connections 34 are deflected from a straight line path by means of idler sheaves 36 disposed at opposite ends 30 of the hopper adjacent the respective transverse walls 20 and 21, and in alignment with the winding sheaves 35 secured to the shafts 33.

By referring to Figure 2, it will be seen 35 that the side doors are operated independently of each other and of the center doors, shaft 33 being operated by means of a transversely extending shaft 37 having a worm and gear connection 38 with the shaft 33. The shaft 37 has one end extended to the 40 side of the car and is adapted to be actuated by any suitable pawl and ratchet mechanism as indicated conventionally at 39 in Figure 2. For operating the inner or center dumping 45 doors G, a longitudinally extending shaft 40 is provided being located between the center sills. Mounted on the shaft 40 are a series of sets of winding sheaves 41—41 disposed side by side, extending in opposite 50 directions, to which flexible connections 42 are secured, passing through perforations 43 in the center sills and connecting with the respective doors G. The flexible connections 42 are deflected by idler sheaves 44 mounted 55 on the transverse hopper end walls and adjacent to the idler sheaves 36 hereinbefore described. By thus deflecting the flexible connections from a straight line path between the respective shafts and doors a direct pull 60 is obtainable on the doors irrespective of the location of the shafts. At the outer ends of the hoppers said sheaves 36 and 44 are carried by a common pivot 45 which is carried at one end by a bracket 46 depending from 65 the inclined end wall B of the car, and at

the other end by means of a bracket 47 disposed on the inner face of the transverse end walls 21. At the inner ends of the hoppers adjacent the central crossbeams two sets of said idler sheaves 36 and 44 are disposed 70 on a common pivot 48 having the opposite ends thereof carried by brackets 49 secured to the transverse walls 20 of the crossbeam. Said sets of idler sheaves are separated by means of a ferrule 50. Each flexible connection 34 and 42 is connected to the door beneath the same and lengthwise thereof by means of an adjustable eyebolt 51, said flexible connection extending outwardly 75 from and beyond the side edge of the door 80 to which it is attached, being guided past the same by means of a guide bracket 52, having an opening 53 through which the chain passes, the bracket 53 being rigidly secured to the door. 85

The shaft 40 is adapted to be operated from a cross shaft 54 having one end or both ends extended to the respective sides of the car and there mounted in suitable bearings 55 carried by a bracket plate 56 depending 90 from the side wall A of the car. The shaft 54 is adapted to be actuated by any suitable ratchet mechanism as indicated conventionally at 57. The worm and gear for the shaft is carried in a housing 58 secured to the centersill of the car, and disposed partly within the same. Said worm and gear is indicated conventionally at 59.

In order to properly divert the ballast or other lading to the desired sides of the rail, I have provided longitudinal diverting members J which extend lengthwise of and beneath the hoppers and which are preferably pivotally mounted as indicated at 60 100 on smaller fixed diverting members or partitions 61 and constitute extensions thereof. Each said diverting member 61 is preferably of inverted V-shape having oppositely disposed downwardly inclined flanges presenting shedding surfaces 62—62. Said member 61 is connected with the transverse end walls of the respective hoppers by means of angles 63—63 placed back to back and secured to the said walls and having the interengaging flanges 64—64 of the angles diverging 105 on either side of the member 61 and secured to the respective flanges as indicated at 65. Each said diverting member J is so arranged that it may be held to form a continuation of the side door F but on a somewhat lower level and the material is then diverted to the center of the track, the diverting member being held in the desired position by connections or chains indicated conventionally as at 66, said connections being 110 fixed to the member J, and secured to the car structure by means of hooks 67 secured to the car structure at the sides and also near the center of car, or said diverting board J may be turned outward as indicated 115 120 125 130

in dotted lines in Figure 2, in which case it will constitute a prolongation of the door G and divert the material to side of the rail when the side door F is opened. Said member J is then supported in such position by means of the connections 66 depending from the hooks 67 carried by the side of the car.

In its preferred form, each member J consists of a metal plate having the margins 10 suitably rigidified by flanging as indicated at 68, thereby forming a pan-shaped member, and a filling piece of lumber substantially equal in depth to the said flanges is used within said pan whereby a shedding 15 surface is obtained on both sides of the said member.

Base plates 69 are provided at each end of the diverting member for the purpose of preventing overflow at the ends of the hoppers and thereby flooding the rail. It will be noted that the positioning of the member J to divert the load in a given direction does not at any time preclude the possibility of opening both doors of a pair at one 25 time and permitting the lading to discharge on both sides of the rail simultaneously, a feature which is advantageous in ballasting, it being often desirable to discharge on both sides of the rail simultaneously.

Although I have shown herein and described what I now consider the preferred embodiments of my invention, the same is merely descriptive, and I contemplate all changes and modifications as come within 35 the scope of the claims appended hereto.

What I claim is:

1. In a car of the character described, the combination with a car body having longitudinally arranged sets of hoppers on each 40 side of the center sill; of hinged center dumping doors for said hoppers, said doors being hinged on longitudinally extending axes and being movable towards each other in an opening direction to discharge the load between the rails; a longitudinally extending common operating shaft for said doors and located therebetween; flexible connections between the shaft and the respective doors; and means for reversing the direction of the pull between the shaft and the doors to close the doors.

2. In a car of the character described, the combination with a car body having longitudinally extending center sills and a longitudinally arranged hopper on each side thereof, each said hopper having a door hinged adjacent the center sill, said doors of the respective hoppers being movable towards each other in an opening direction 55 and the pivotal axes of said doors being substantially parallel with said operating shaft; of a longitudinally extending operating shaft disposed between the sills; flexible connections between the shafts and the respective doors; and means for reversing the di-

rection of the pull between the shaft and the doors for effecting simultaneous closing movement of said doors.

3. In a car of the character described, the combination with a car body having longitudinally arranged sets of hoppers on each side of the center sill; of a transversely extending hollow crossbeam between the ends of adjacent hoppers; hinged center dumping doors for said hoppers, said doors being movable towards each other in an opening direction; a longitudinally extending operating shaft located between the said doors; guide elements disposed in the said hollow crossbeam and arranged to present 75 guiding surfaces substantially parallel to said shaft, and flexible connections between the shaft and the respective doors, each said flexible connection passing over one of said guide elements.

4. In a car of the class described, the combination with a car body provided with a plurality of longitudinally arranged hoppers disposed on opposite sides of the center sill, each of said hoppers being provided 80 with a pair of door openings for side and center dumping; of a transversely extending hollow member disposed between the ends of adjacent hoppers; doors hinged along their upper edges for closing said openings; a longitudinally extending shaft for operating the center dumping doors simultaneously; longitudinally extending shafts for operating the side dumping doors independently of each other and of the center doors; flexible 85 connections from the doors to their respective operating shafts; and idler pulleys disposed in the transverse member, said pulleys being adapted to deflect the connections from a straight line path.

5. In a car of the character described, the combination with a car body having a longitudinally extending center sill and a longitudinally arranged hopper on each side thereof, each said hopper having a pair of door openings and oppositely swinging doors for closing the same, one of said doors opening inwardly of the car and the other opening outwardly thereof, said doors being hinged at their upper end and inclined 100 downwardly towards each other thus forming four sets of longitudinally extending doors; of transversely extending walls at the ends of said hoppers; three sets of longitudinally extending shafts extending past the said transverse end walls of the hoppers, one of said shafts being located between the hoppers and the other shafts located respectively on the outer sides of said hoppers, said central shaft being adapted to operate 105 the inner doors of the respective hoppers in unison, and the outer shafts being adapted to operate the outer doors independently of each other and of the inner doors; connections from each door to the shaft operating 110

- the same, said connections being disposed at the ends of the hopper adjacent the said transverse wall, and sets of two sheaves mounted on a common pivot and disposed 5 at each end of the hopper, said sheaves forming means for deflecting the flexible connections from the shafts to the doors, one of the sheaves of each set forming a deflector for the connection with the outer door 10 and the other sheave forming a deflector for the connection with the inner door.
6. In a car of the class described, the combination with a car body provided with longitudinally arranged hoppers disposed on 15 opposite sides of the center sills, each hopper comprising oppositely disposed doors hinged at their upper ends and meeting with their free edges forming a V-shaped hopper having the apex thereof disposed 20 centrally over the rail; of diverting boards hinged centrally beneath said hoppers and movable to deflect the entire load either to one side or the other of the rail.
7. In a car of the class described, the combination with a car body provided with longitudinally arranged hoppers disposed on 25 opposite sides of the centersill, each said hopper having the apex thereof meeting centrally over the rail; of a member extending 30 longitudinally beneath the apex of the hopper and movable to deflect the load from one side or to the other of the rail; and means for maintaining said member in an inclined position, said means comprising a 35 series of hooks carried by the car body and flexible elements each having one end thereof secured to the swinging edge of the movable member and the opposite end being adapted to be carried by one of said hooks.
- 40 8. In a car of the character described, the combination with a car body having a longitudinally extending center sill and a longitudinally arranged hopper disposed on each side thereof, each hopper having a pair 45 of door openings and oppositely swinging doors for closing the same, said doors being hinged at their upper edges; of an extraneous longitudinally extending diverting partition at the bottom of each hopper; and 50 an extension for said partition movable from one side of the hopper to the other for the purpose of deflecting the load when dumped.
9. In a car of the character described, the 55 combination with a car body having a longitudinally extending center member and a longitudinally extending hopper disposed on each side thereof, each hopper having a pair of door openings and oppositely swinging doors for closing the same, each of said doors being hinged at the upper edge; of an inverted V-shaped diverting member beneath each hopper; and a hinged member carried by said diverting member, and constituting an extension for the same, said

member in one position being adapted to deflect the load between the rails and in another position outside of the rails.

10. In a car of the class described, the combination with a longitudinally extending hopper having oppositely disposed doors hinged at their upper edges; of an extraneous movable diverting member adapted in one position to divert the entire load to one side of the hopper and in another position to divert the load to the opposite side of said hopper, said diverting member being so arranged as to permit both doors of said hopper to open simultaneously.

11. In a car of the class described, the combination with a car body having a longitudinally extending hopper including oppositely disposed doors hinged at their upper edges and inclined downwardly towards each other; of a movable diverting member 35 adapted to be disposed in an inclined position beneath either of the doors whereby the load may be deflected to one side or to the other of the hopper; and a baffle end plate 40 on the diverting member.

12. In a car of the class described, the combination with a car body provided with longitudinally arranged hoppers disposed on opposite sides of the center sill, each said hopper comprising oppositely disposed doors 95 hinged at their upper edges; of a member extending longitudinally beneath the apex of each hopper and adapted to be positioned to form in one position a continuation of certain of said hopper doors to adapt the car 100 for center dumping and in another position to form a continuation of the remaining hopper doors to adapt the car for side dumping.

13. In a car of the class described, the combination with a car body having a longitudinally extending hopper defined by transversely extending walls and oppositely disposed doors hinged at their upper edges and inclined downwardly towards each other; of an inverted, substantially V-shape member comprising diverging flange sections disposed beneath the hopper and longitudinally thereof; and angles secured to each flange of said member, said angles being bent to extend upwardly and secured to the transverse walls of the hopper.

14. In a railway car, the combination with girder sides; of a longitudinal center sill; transversely extending gusset members secured to the car sides; a vertical member extending across the plane of the center sill and secured thereto and connecting the inner ends of said transverse gusset members, said vertical member terminating an appreciable distance from each side wall of the car; and inclined shedding plates secured to both the gusset plate and to the vertical member, said shedding members being also secured to the gusset plate independently of 120 125 130

the vertical member and to the vertical member independently of the gusset plate.

15. In a car of the class described, the combination with a car body having a plurality of longitudinally arranged sets of hoppers on each side of the center sill, each set of hoppers being defined by a pair of longitudinally extending doors hinged at their upper edges and inclined downwardly to 10 wards each other and a transverse vertical wall at each end thereof, said transverse vertical walls intermediate the adjacent ends of the hopper forming portions of a transversely extending crossbeam; of an inverted V-shaped diverting member disposed beneath each hopper and extending beyond the said transverse walls thereof; and a pair of angle members placed back to back and secured to said transverse walls, said angles 20 being extended downwardly and diverging to opposite sides of the diverting member and secured thereto.

16. In a car, the combination with a dump door; of an operating shaft, a flexible connection extending between the shaft and the door, said connection being adjustably secured to the door lengthwise thereof and projecting beyond the side edge thereof; and a bracket secured to the door near the 30 edge thereof, said bracket having a hole

therein through which the said flexible connection extends.

17. In a car of the class described, the combination with a car body provided with longitudinally arranged V-shaped hoppers 35 disposed on opposite sides of the center sills, of a swinging diverting member extending longitudinally beneath the hopper, said member being formed of a metallic plate having rigidifying marginal flanges 40 forming a panlike structure and a filling member of wood disposed within the said pan providing for shedding surfaces on either side of said diverting member.

18. In a car of the class described, the 45 combination with a car body provided with longitudinally arranged hoppers disposed on opposite sides of the center sill, each of said hoppers being provided with door openings for side and center dumping; of 50 doors hinged along their upper edges, for closing said openings; a longitudinally extending shaft for operating the center doors simultaneously; and means for operating the side dumping doors independently of 55 the center doors.

In witness that I claim the foregoing I have hereunto subscribed my name this 2d day of May 1924.

ARGYLE CAMPBELL.
